(57) **CLAIM**

The ornamental design for an endoscope, as shown and described.

DESCRIPTION

FIG. 1 is a perspective view of an endoscope.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is an enlarged end view thereof taken along line 8-8 in FIG. 5, which omits the internal structure; and,

FIG. 9 is an enlarged end view thereof taken along line 9-9 in FIG. 5, which omits the internal structure.

The portion of the endoscope shown in broken lines is for the purpose of showing environmental structure only and forms no part of the claimed design.

The dash-dot-dash lines represent the boundaries of the claimed design and form no part thereof.
